CLAIM

The ornamental design for a light switch cover plate, as shown and described.

DESCRIPTION

FIG. 1 is a front perspective view of a light switch cover plate in accordance with my new design;

FIG. 2 is another front perspective view thereof;

FIG. 3 is a front elevation view thereof;

FIG. 4 is a top view thereof;

FIG. 5 is a first side elevation view thereof;

FIG. 6 is a second, opposite side elevation view thereof;

FIG. 7 is a bottom view thereof; and,

FIG. 8 is another front perspective view thereof.

The broken lines represent unclaimed subject matter and form no part of the claimed design. The dot-dash broken lines define the boundaries of the claimed design and form no part thereof. The back of the light switch cover plate is not visible during use and forms no part of the claimed design.
